United States Patent Office

Des. 183,415
Patented Aug. 26, 1958

183,415
SPECTACLE FRAME FRONT

Marcel Arnaut, Paris, France, assignor to Societe Industrielle de Lunetterie, Paris, France

Application April 3, 1956, Serial No. 40,885

Claims priority, application France March 5, 1956

Term of patent 14 years

(Cl. D57—1)

Fig. 1 is a face view of a spectacle frame front embodying my new design;

Fig. 2 is a top plan view thereof;

Fig. 3 is a rear elevational view; and

Fig. 4 is a side elevational view thereof.

I claim:

The ornamental design for spectacle frame front, as shown.
